UNITED STATES PATENT OFFICE.

ARTHUR J. WIDMER, OF WEBSTER GROVES, MISSOURI, ASSIGNOR, BY MESNE ASSIGNMENTS, TO WIDMER ENGINEERING COMPANY, OF ST. LOUIS, MISSOURI, A CORPORATION OF MISSOURI.

PLASTER-CEILING SUPPORT.

1,251,151.

Specification of Letters Patent. Patented Dec. 25, 1917.

Application filed November 13, 1916. Serial No. 131,016.

To all whom it may concern:

Be it known that I, ARTHUR J. WIDMER, a citizen of the United States, and a resident of Webster Groves, in the county of St. Louis and State of Missouri, have invented a new and useful Improvement in Plaster-Ceiling Supports, of which the following is a specification.

This invention relates to supporting plaster ceilings from ribbed concrete floors, and particularly to ceilings having a ground consisting of plaster boards. The invention is applicable also to supporting ceilings having metal lath or other ground for the plaster, and to supporting sheet metal ceilings.

The invention consists in an improved form of sheet metal anchor strip embedded in the concrete and provided with integral tongues projecting down through the ceiling boards or metal lath for supporting the ceiling. The invention also consists in the improved form of supporting plates for the edges of the ceiling boards to rest on.

Further objects and details of the invention appear in connection with the following description of the floor construction shown in the accompanying drawings, which embodies the invention in a preferred form. The invention is further defined in the claims.

In the drawings, wherein the same reference characters designate the same or similar parts in the several views,

Figure 1 is a side elevation of the improved anchor strip, showing it in place on the floor forms, ready for pouring the concrete to make the floor rib;

Fig. 2 is a cross-section of the same, on the line 2—2 in Fig. 1, looking in the direction of the arrows;

Fig. 3 is a longitudinal section of the finished floor, prior to plastering it, part of the rib being broken away to show an anchor strip in side elevation;

Fig. 4 is a cross-section of the rib shown in Fig. 3 on the line 4—4 in Fig. 3, looking in the direction of the arrows;

Fig. 5 is a bottom plan view of the finished floor prior to plastering the ceiling, parts of the plaster boards being removed to disclose the rib;

Fig. 6 is a bottom view of a plaster board supporting plate;

Fig. 7 is a side elevation of an anchor strip ready for placing on the forms;

Fig. 8 is a plan view of the anchor strip; and

Fig. 9 is a fragmentary view similar to Fig. 3 showing a modified form of anchor strip.

Reinforced concrete floors having strengthening ribs on their under sides are commonly molded in place in temporary forms or centering, the ribs and floor slab being poured simultaneously; and after the concrete has hardened sufficiently for the floor to be self-supporting, the forms are removed and the ceiling is applied from below. Heretofore, ties have been embedded in the ribs with their lower ends depending below the concrete to support the ceiling, but this method of construction requires special provision to be made in the forms for the ties. Moreover, where separate ties are used, care must be taken to space them properly and to secure them well against accidental displacement during the placing of the reinforcing bars and concrete in the ribs.

The ceiling supports 11 shown in the drawings are continuous strips of metal, which are nailed or tacked to the forms 12 in the middle of each rib space prior to placing the materials which compose the ribs 13.

In the forms of construction illustrated in Figs. 1 to 8, inclusive, the ceiling support 11 consists of a strip of metal which has tongues 14 an inch or more in length struck down from its middle portion at equal distances apart. The intervals between the tongues may be six to eight inches in length, and are slotted longitudinally to form three strips. The middle strip 15 is struck up to form an inverted V-shaped anchor for embedding in the concrete of the rib 13. This operation shortens the strip 11, and the side strips 16 are folded under the unslotted portion of the strip to take up their surplus length, as shown in Fig. 7. Instead of the folds 17 formed by the surplus length of the side strips being laid under the unslotted portion of the strip, they may be made at the middle of the side strips and laid back on themselves, as shown in Fig. 9. This construction makes the strip 11 rigid enough to be handled without losing its shape.

After the forms 12 are removed, the

tongues 14 are bent down, and the plaster boards 18, or other suitable ground for the plaster, are placed across the ribs 18 spanning the spaces between the tongues. Narrow spaces are left between the plaster boards for the tongues to project down through, and plates 19 are arranged across these spaces and secured to the tongues to hold up the plaster boards. The plates 19 have holes 20 through which the ends of the tongues 14 pass, and ribs 21 for stiffening them. A thick coat of plaster 22 is applied to the lower surface of the plaster boards, covering up the plates and tongues, and filling the spaces between the plaster boards.

In the construction shown in Fig. 9, the anchor strip 11 has two tongues 23 between each anchor portion 15 for bending under the plates 19 at both edges, instead of a single tongue for each plate.

From the description and drawings it is evident that no special provision need be made in the forms for the anchor strips, and that no special form or arrangement of reinforcement is required for use with the anchor strips. The invention is not restricted to the precise shapes and arrangements of the anchor strips and plates shown and described.

30 I claim the following as my invention:

1. A floor construction comprising concrete ribs, continuous strips of sheet metal narrower than said ribs and embedded in the middle region of said ribs, portions of said strips being slotted and bent up in undulations extending into said ribs, and portions being slotted to form tongues projecting below the lower edges of said ribs, and ceiling boards spanning beneath said ribs and supported by said tongues.

2. A supporting device for the ceiling of a concrete floor, said device comprising a continuous strip of sheet metal of undulating form embedded in the under side of the floor, portions of said strip being slotted and bent to project up into the concrete, other portions of said strip being slotted and bent to form downwardly extending tongues which project below the floor, and metal

plates supported on said tongues and on 50 which the ceiling rests.

3. A continuous anchor strip for embedding in a concrete floor for supporting a ceiling made of plastic material, said anchor strip comprising a series of tongues, and 55 slit portions intervening between said tongues, said slit portions being separated and one part bent out of the plane of the strip on the side opposite said tongues to form loops for embedding in the concrete. 60

4. A continuous anchor strip for embedding in a concrete floor for supporting a ceiling made of plastic material, said anchor strip comprising a series of tongues, and 65 slit portions intervening between said tongues, said slit portions being separated and one part bent out of the plane of the strip on the side opposite said tongues to form loops for embedding in the concrete, the surplus metal of the remaining slit portions being folded back into the plane of the strip. 70

5. A continuous anchor strip for embedding in a concrete floor for supporting a ceiling made of plastic material, said anchor strip comprising a series of tongues, and 75 slit portions intervening between said tongues, said slit portions being separated and one part bent out of the plane of the strip on the side opposite said tongues to 80 form loops for embedding in the concrete, the remaining slit portions being crimped to reduce their length to correspond to the reduction in length resulting from bending said bent portions out of the plane of the 85 strip, said crimped portions being folded flat against the plane of said strip.

6. A metal supporting plate for plaster board ceilings, said plate having a longitudinal rib across its middle, and a hole in the 90 apex of said rib at the middle of the plate adapted to receive a supporting tongue, whereby said tongue may be readily centered in said slit and bent at an acute angle to center and support said plate. 95

Signed at St. Louis, Missouri, this ninth day of November, 1916.

ARTHUR J. WIDMER.
